UNITED STATES PATENT OFFICE.

CASIMIR RYSIEK, OF CHICAGO, ILLINOIS.

TABLECLOTH-STRETCHER.

1,386,205.

Specification of Letters Patent. Patented Aug. 2, 1921.

Application filed March 21, 1921. Serial No. 454,119.

To all whom it may concern:

Be it known that I, CASIMIR RYSIEK, a citizen of the United States of America, residing at Chicago, in the county of Cook 5 and State of Illinois, have invented certain new and useful Improvements in Tablecloth-Stretchers, of which the following is a specification.

My present invention relates generally to 10 devices for stretching fabrics, and more particularly to a device for stretching circular table cloths, center pieces and the like or those of a shape other than rectangular, my invention being adapted to oval or irregular 15 shaped table cloths, center pieces, and the like in connection with which ironing as done at the present time is a tedious unsatisfactory job more often attended by failure than success.

20 The primary object of my invention is the provision of a device of this character which may be readily set up and taken down, and which may be easily and quickly adapted to cloths of various shapes and sizes within 25 diametrical limits of the stretching frame.

With these and other objects more clearly appearing in the following description my invention resides in the stretching device shown in the accompanying drawing, which 30 forms a part of this specification, and in which,

Figure 1 is a top plan view of the complete apparatus in operative position,

Fig. 2 is a side elevation thereof,

35 Fig. 3 is a horizontal section through the supporting frame taken substantially on line 3—3 of Fig. 2,

Fig. 4 is an enlarged radial section through the stretching frame,

40 Fig. 5 is a detail side view of one of the stretching hooks, and

Fig. 6 is a detail side view of one of the connecting links.

Referring now to these figures, the stretching frame, forming a part of my invention and which is preferably circular in form and composed of two substantially semicircular sections, includes an outer wire rim whose sections 10 and 11 may be joined in operative position by means of tubular couplings 12, preferably secured to the section 11 and adapted to receive the free ends of the sec-

tion 10. The sections 13 and 14 of the hub, each section of which is connected to its respective rim section by a series of radial stretching arms 15, are preferably formed of wood or similar material so that the inner ends of these arms 15 may be connected thereto in some simple effective manner as for instance by means of staples 16, and section 14 is furthermore provided with a swinging hook 17 adapted to engage a staple or eye 18 of the section 13 so that with the ends of the rim section 10 disposed within the tubular couplings 12, and the hook 17 is engaged as shown in Fig. 1, the two sections of the stretching frame will be effectively held in the operative position. By disconnecting the hook 17, the sections may be readily detached and superimposed upon one another for storage within minimum space.

In the operative position of the two sections of the stretching frame, this frame as a whole is adapted to be supported upon a stand shown particularly in Figs. 2 and 3 and including an upright in upper and lower sections 19 and 20, the latter of which has an upstanding dowel pin 21, and the former of which has at its lower end a bore to receive the pin so that the upper section 19 can in the effective position be rotated. The upper section has apertured outstanding brackets 22 adapted to receive the depending angular inner ends 23 of a series of outstanding and upwardly inclined supporting arms 24, each of which has at its upper end an angular upward extension 25 shaped and adapted to receive therein the rim of the stretching frame. 90

The lower section 20 of the supporting stand has a lower cross piece 26, to which the lower end of the upright is secured and to which it is also braced by inclined brace arms 27 in diametrically opposing relation. Other brace arms 28 also serve to assist in holding the upright in effective position, these latter brace arms extending at right angles to the brace arms 27 and being hingedly connected at one side at 29 to the lower section 20 of the upright so as to fold laterally thereagainst in the inoperative position. Each of these brace arms 28 has a hook 30 at its other side to engage an

2
eye 31 on the upright, to hold the same in place.

Each of the radial arms 15 of the stretching frame is bent at its outer end as at 32 around the rim of the stretching frame, and each is fashioned with a terminal eye 33 just inside of the rim so that the several arms may be connected in properly spaced relation adjacent to their outer ends by connecting or spacing links 34 whose bent ends 35 engage the eyes 33.

Each of the radial arms 15 is also provided with one or more, preferably two, stretching hooks 36, which extend between 15 the arms, each hook having a curved and sharpened free end 37 and having its opposite end bent to form a helix 38 disposed around and adapted to frictionally grip the respective stretching arm, the helix preferably projecting inwardly toward the hub of the stretching frame so that when the free ends of the hooks around the stretching frame are engaged with a plurality of points around the peripheral edge of the 25 circular fabric to be stretched, they can yield but slightly toward the center of the frame but will be held in non-slipping relation upon the stretching arms.

It is thus obvious that in use it is simply 30 necessary to engage the stretching hooks around the stretching frame with a plurality of points around the periphery of the piece to be stretched, the fabric being laid upon the upper surface of the stretching 35 frame after the latter has been disposed upon the supporting arms 24. The operator may then proceed around the stretching frame, shifting the hooks outwardly along the stretching arms 15 until the fabric is 40 properly stretched in all directions, after which it is left to dry.

It is further obvious that due to this construction circular and oval fabrics such as table cloths, center pieces, doilies, napkins 45 and the like may be effectively stretched and dried, with or without scalloped or other irregular edges, and with or without lace or other embroidery therearound.

It is furthermore obvious that the device 50 as a whole may be readily and quickly set up in operative position and as readily taken down and stored in minimum space when the desired operation has been completed, and it becomes apparent that due to these 55 several functions and advantages my invention presents an apparatus which is highly effective and will be strong and durable in use.

I claim:

60 1. A stretching frame of circular form having a hub and a rim, a plurality of radial arms extending between the hub and the rim, and stretching hooks on the arms and extending therebetween and the 65 frame, said hooks having means to engage

and adjustably hold the same on the arms as described.

2. A stretching frame of circular form having a hub and a rim, a plurality of radial arms between the hub and the rim, and stretching hooks having means to frictionally adjustably engage and support the same on the arms.

3. A stretching frame of circular form including a hub and a rim, a plurality of stretching arms radiating from the hub to the rim, and stretching hooks projecting from the arms, having outer curved and sharpened ends, and each provided at its inner end with a helix around and adapted to frictionally grip one of the said stretching arms.

4. A stretching frame comprising a hub, a rim of circular form, stretching arms radiating from the hub to the rim, each of said arms having a bent portion surrounding the rim and terminating in an eye within the rim, spacing and connecting links joining the eyes of the several arms to space and connect the latter adjacent to the rim, and stretching hooks adjustable on the arms as described.

5. A stretching frame of circular form having a hub, a rim, radial arms between the hub and the rim, stretching hooks on the arms, said hub and said rim being each formed in two sections, and means for detachably connecting the sections to hold the frame in operative position.

6. A stretching frame of circular form 100 having a hub, a rim, radial arms between the hub and the rim, stretching hooks on the arms, said hub and said rim being each formed in two sections, and means for detachably connecting the sections to hold the 105 frame in operative position, including tubular couplings co-operating with the rim sections and a hook and eye carried by the hub sections.

7. An apparatus of the character described consisting of a supporting stand having an upright in detachable sections of which the upper section is rotatable with respect to the lower section when the sections are connected, a substantially circular 115 stretching frame, a plurality of supporting arms detachably engaged with the upper section of the upright and having upwardly and outwardly inclined portions terminating in upwardly angular outer ends within 120 which the stretching frame is detachably seated, and supports for the lower section of the upright.

8. An apparatus of the character described consisting of a supporting stand 125 having an upright in detachable sections of which the upper section is rotatable with respect to the lower section when the sections are connected, a substantially circular stretching frame, a plurality of supporting 130

arms detachably engaged with the upper section of the upright and having upwardly and outwardly inclined portions terminating in upwardly angular outer ends within 5 which the stretching frame is detachably seated, and supports for the lower section of the upright, including a plurality of in-

clined brace members certain of which are foldable with respect to the others for the purpose described.

10

In testimony whereof I have affixed my signature.

CASIMIR RYSIEK.
